UNITED STATES PATENT OFFICE

FRED E. ASELTINE, OF DAYTON, OHIO, ASSIGNOR TO DELCO PRODUCTS CORPORATION, OF DAYTON, OHIO, A CORPORATION OF DELAWARE

CHARGE FORMING DEVICE

Application filed September 16, 1929. Serial No. 392,809.

This invention relates to charge forming devices for internal combustion engines, and more particularly to devices of this character which comprise a plurality of primary carburetors which deliver a primary mixture of fuel and air to a plurality of secondary mixing chambers located adjacent the engine intake ports, and in which the primary mixture is mixed with additional air under certain operating conditions.

A device of this character is disclosed in the copending application of Fred E. Aseltine, Serial No. 286,975, filed June 20, 1928, to which reference may be had for a full disclosure of the device described herein.

The principal object of the present invention is to provide novel means for temporarily enriching the mixture during the acceleration period immediately following any opening movement of the throttle, and more particularly, to provide a device of this character which is effective only after opening movements of the throttle, which take place when the engine is operating at speeds above a certain predetermined speed.

The device disclosed in this application is similar to that disclosed in the above mentioned copending case, and differs therefrom only in the fact that such case discloses a fuel pump operated by the primary throttle and which is effective to pump fuel on every opening movement of said throttle, while the device disclosed in this application comprises a pump which is operated by the secondary or air throttle and is, therefore, effective to pump fuel into the mixing chambers only on opening movements of said air throttle. In devices of this character, the air throttle does not open until the engine is operating at a predetermined speed, generally a speed corresponding to a vehicular speed of from 15 to 25 miles per hour.

Further objects and advantages of the present invention will be apparent from the following description, reference being had to the accompanying drawings, wherein a preferred embodiment of one form of the present invention is clearly shown.

In the drawings:

Fig. 1 is a fragmentary, plan view of a

charge forming device in which the present invention is embodied.

Fig. 2 is a side elevation of the carburetor unit forming part of the device.

Fig. 3 is a longitudinal section through a charge forming device embodying the present invention and an engine intake port with which such device is associated.

Fig. 4 is a transverse section on the line 4—4 of Fig. 3.

Fig. 5 is a fragmentary, transverse section on the line 5—5 of Fig. 3.

Fig. 6 is a plan view of the entire charge forming device.

The device disclosed comprises a main air manifold 10, having three outlet branches, the middle branch 12 being shown herein. Each of these branches communicates with one of the intake ports 14 of a multicylinder engine. The outlet branches are each provided with an attaching flange 16 for securing the manifold to the engine block in the usual manner, and a flange 18 to which the carburetor unit is secured.

The carburetor unit comprises a main housing 20, having an attaching flange 22, adapted to be secured to the flange 18 by screws 24. An air inlet coupling 28 is secured in position to register with an opening in the upper wall of the housing 20, in any suitable way and may be connected with an air cleaner if desired. A casting 30, in which the passages supplying fuel to the nozzles are formed, is secured by screws to the lower wall of housing 20, and a sheet metal fuel bowl 32 is held tight against an annular shoulder 34 on the housing 20 by any suitable means. Fuel is conducted from a main source of supply to the fuel bowl through a conduit (not shown) and the flow of fuel to the bowl is controlled by a float 36, operating in the usual manner to maintain a substantially constant level of fuel therein.

Fuel flows from the bowl 32 to a plurality of primary fuel nozzles 38, one of which is located in each of the primary mixing chambers 40, the construction of which is briefly described hereinafter. The fuel conduit between the fuel bowl and the nozzles comprises the vertical fuel passage 42 communicating

at its upper end with the horizontal fuel canal 44, which connects with each of the nozzles 38 through an orifice 46. Fuel is admitted from the fuel bowl to the passage 42 5 at all engine speeds, through a fixed metering orifice 48 and at high speeds additional fuel is admitted through an orifice 50 controlled by a valve 52, operated in the manner set forth in the above mentioned application. 10 This operating means forms no part of the present invention and need not be described further herein.

Fuel is lifted from the fuel bowl through the above described fuel passages and nozzles 15 38 to the primary mixing chambers by the suction therein. Opening movements of the throttle cause a reduction in mixing chamber suction which might permit the fuel column to drop sufficiently to cause a temporary fuel 20 starving of the engine unless means are provided to prevent this action. For this purpose a check valve 54 is provided in an enlarged chamber 56 at the junction of the channels 42 and 44, and on reduction of mixing 25 chamber suction, seats on the bottom of the chamber, preventing downward flow of fuel.

Each primary fuel nozzle is provided with a main fuel outlet 58 in the top of the nozzle and a secondary fuel outlet comprising two 30 orifices 60 and 62 in the vertical wall of the nozzle near the bottom of the mixing chamber. At relatively high speeds, the mixing chamber suction is sufficient to lift fuel from the main outlet as well as from orifices 60 35 and 62. At idling, or low speed operation under load, however, the suction is enough to lift fuel only to some point between the top of the nozzle and the orifices 60 and 62, fuel flowing from these orifices by the action of 40 gravity under such operating conditions. Each nozzle is provided with a restricted fuel metering orifice 63. The primary mixing chambers comprise the enlarged anterior ends of the primary mixture passages 64, 45 which are parallel to each other and close together, as indicated in Fig. 4. When the carburetor is attached to the manifold, these passages register with conduits which convey the primary mixture to the secondary mixing 50 chambers, as fully disclosed in the application above referred to. Restrictions 66 separate the primary mixing chambers from the remainder of the mixture passages to reduce the velocity of flow past the fuel nozzles for 55 a purpose fully set forth in the above mentioned copending application.

A single throttle valve 68, which extends across all the primary mixture passages, controls the flow therethrough and is provided 60 with grooves 70, which register with said mixture passages. This throttle is operated in a manner hereinafter more fully described. The middle primary mixture passage communicates with a tube 72 fixed in the manifold 65 branch 12. This tube constitutes one of the

primary mixture conduits above referred to and conveys the primary mixture to the secondary mixing chamber located in the middle branch of the manifold.

Nearly all of the air entering the carburetor flows through the inlet coupling 28 and is controlled by the main air valve 74, normally held against a seat 76 by a spring 78, received between the valve and a flange 80, projecting from a sleeve 82, slidably mounted 75 on a stationary guide sleeve 84, fixed in the housing 20, and serving also as a guide for the stem 86 to which the air valve is secured. When it is desired to choke the carburetor to facilitate starting of the engine, the flange 80 is adapted to be lifted by means not shown herein, but fully described in the above application, until the upper end of the sleeve 82 engages the air valve to hold it closed. Sufficient air to carry the starting fuel from 85 the nozzles to the intake ports is admitted through an elongated slot 87, formed in a plate 88, secured to the housing 20, as shown in Fig. 3.

The valve 74 admits air to the air chamber 90, from which air flows to the primary mixture passages through an orifice 92 in the bottom of the air chamber and to the secondary mixing chambers through a passage 94, which connects with the inlet of the manifold 10. 95 The flow of air through this passage is controlled by a manually operable throttle 96, secured to a shaft 97, rotatably mounted in the main housing.

The operating connections for the throttle 100 valves comprise an operating arm 98 provided with an orifice 100 in its free end, in which some suitable form of operating connection extending to a point convenient to the operator of the vehicle is adapted to be secured. This arm is secured in any desirable manner to a spindle 102, projecting from the end of the primary throttle and is connected by a lost motion connection, hereinafter described specifically, to an arm 104, secured 105 to the shaft 97 by a split clamp or other suitable means. The lost motion connection comprises a link 106, pivotally connected to the arm 98 and provided with a slot 108 through 110 which a pin 110, screwed into the arm 104, projects. A regulating screw 112 is threaded in lugs 114, projecting from the link, and may be adjusted to regulate the length of the slot 108, the upper end of said screw constituting the lower end of the slot. A tension 115 spring 116 is connected at one end to the upper end of the link and at the other end, to the pin 110. This spring tends to hold the pin against the upper end of the slot 108, but with both throttles closed, the parts are in the 120 position shown in Fig. 2, with the pin 110 in engagement with the regulating screw 112. As the operating arm 98 is rotated in a counter-clockwise direction to open the primary throttle, the link 106 moves downward. 125

ly to a position where the upper end of the slot 108 strikes the pin 110 before the operating arm 104 of the air throttle is moved, so that the primary throttle is partly opened before the air throttle begins to move. The screw 110 operates as a stop to limit the closing movement of the primary throttle and adjustment of the screw regulates the position of the primary throttle at idling. The above described lost motion connection is generally so adjusted that the primary throttle is opened to a position permitting an engine speed corresponding to a vehicular speed of 15 to 25 miles per hour on a level before the air throttle starts to open.

On opening of one or both of the throttle valves, the suction in the air chamber 90 is increased and the valve 74 is opened to admit additional air and increase the quantity of mixture supplied the engine. The opening of this valve is retarded to prevent fluttering thereof and to restrict the admission of air to prevent a temporary leaning of the mixture whenever the throttles are opened. To this end a dashpot is provided which comprises a cylinder 120, receiving fuel from the reservoir 32 and a piston 122, secured to the lower end of the valve stem 86 by any suitable means. Fuel is admitted to the cylinder on closing movements of the air valve by a check valve (not shown) which also operates to prevent escape of fuel therefrom when the valve is open. The specific construction of this dashpot forms no part of this invention and it may be of any conventional form.

As hereinbefore stated, additional fuel is supplied to the mixing chambers following any opening movement of the air throttle 96. To this end a pump is provided comprising a cylinder 130 cast integral with the dashpot cylinder 120, as shown in Fig. 4, and having its lower end closed by a removable plug 132. A pump piston 134 is slidable within the cylinder and is connected by a piston rod 136 to a link 138, which is pivotally connected at 140 to said rod and at 142 to the free end of an operating arm 144, secured to the shaft 97 between the arm 104 and the outside of the main housing.

The plug 132 is provided with a passage 146 connecting the interior of the pump cylinder with the fuel bowl and admitting fuel to the cylinder on the upward stroke of the piston 134, the passage being provided with an enlargement 148 in which is received a check valve 150, which closes the passage 146 on downward movement of the piston.

Reduced portion 152 of the plug 132 projects downwardly therefrom and is provided with a central bore 154 normally closed by cap 156 screwed on the part 152. A restricted orifice 158 connects the bore 154 with the interior of the pump cylinder and a fuel delivery conduit 160 is received in an orifice in the wall of the reduced portion of the plug

152 and communicates with said bore 154. The flow of fuel from the pump cylinder to the delivery conduit is controlled by a valve 162, connected by a wire 164 to a small piston 166, slidably received within a recess 168 formed within the main pump piston. A spring 170 surrounds the wire between the bottom of the piston 166 and the plug 132 normally holding the valve 162 in position to close the orifice 158, as will be more fully described hereinafter.

The fuel delivery conduit extends through that portion of the main housing which constitutes the top of the float bowl, as indicated in Fig. 4, and immediately above the bowl, said conduit connects with a header 172, from which extends three separate delivery pipes 174, 176 and 178, which lead to the various secondary mixing chambers located in the outlet branches of the manifold, one of which is disclosed in full in Fig. 3. To facilitate assembly of the device, any well known form of coupling means such as a union, may be provided in each of the pipes 174, 176 and 178, if desired. These pipes, at their delivery ends, are bent upwardly as indicated in Fig. 3, and extend obliquely through the attaching flange 16 and the walls of Venturi tubes 180, which form the secondary mixing chambers, terminating flush with the lower surface of said Venturi tubes at a point substantially adjacent the point of greatest suction therein. The pump delivery conduits could, obviously, extend into the Venturi tubes rather than terminate flush with the wall, but if so constructed, would tend to produce some disturbances in the air flow adjacent the delivery ends of the primary mixture conduits, which might effect the operation of the device to some extent by reason of eddy currents. For this reason, the construction disclosed herein is deemed more desirable.

It will be clear that the suction and the rate of flow through the Venturi tubes at the point where the pump delivery conduits terminate is at all times high and when the main air throttle is opened, the velocity of flow through these tubes is particularly great. Owing to the presence of a high degree of vacuum and high air velocity at the outlets from these delivery conduits, the fuel issuing therefrom will be partly vaporized and the unvaporized particles which remain will be thoroughly mixed with the mixture passing through the tubes.

The construction of the above described pump mechanism is the same as that disclosed in the earlier copending application, except for the fact that the pump piston is operated in this device by the main air throttle, while in the earlier device, is operated directly by the primary throttle. For a fuller disclosure of this mechanism, particu-

larly the delivery conduits, reference may be had to such earlier application.

The secondary mixing chambers comprise the Venturi tubes 180, previously referred to, there being three of these which are identical in construction and when the device is assembled, are held in position by engagement of a rib 182, formed on the outer surface of the venturi between shoulders 184 and 186 on the manifold and engine block respectively.

The operation of the above described pump is substantially as follows: During the first part of the opening movement of the primary throttle, the pump is ineffective, but on any opening movement of said throttle which is accompanied by a relatively rapid opening movement of the air throttle, the pump piston is moved downwardly and the pressure on the small piston 166 is sufficient to open the valve 162, which is normally closed, substantially simultaneously with the beginning of the movement of the pump piston. The valve 166 is closed at the end of any pump stroke of the pump piston and is held closed by the spring 170 during any upward movement of said piston so that the fuel in the delivery conduits can not return to the pump cylinder and also, the closing of said valve prevents the suction in the Venturi tubes 180 operating to draw fuel from the delivery conduits during normal operation. The delivery conduits are, therefore, kept full of fuel which is injected into the secondary mixing chambers substantially simultaneously with the beginning of any relatively rapid opening movement of the air throttle, and such fuel being supplied adjacent the engine intake ports, is carried into the engine cylinders without perceptible delay. During very slow opening movement of the throttle, the injection of additional fuel into the mixture is not desirable and the valve 162 renders the pump ineffective under such conditions. There is a slight leakage of fuel past the pistons 184 and 166 so that when the pump piston moves very slowly this leakage is sufficient to prevent the building up of sufficient pressure on the piston 166 to collapse the spring 170 and open the valve.

As previously pointed out, the device disclosed herein differs from that disclosed in the above referred to copending application only in the means for operating the pump piston. It has been determined that during operation at all speeds under that speed at which the air throttle begins to open, it is not altogether desirable to supply additional fuel to the mixture following an opening movement of the primary throttle. Under such operating conditions, the suction within the primary mixing chambers is sufficient to draw sufficient fuel from the nozzles to form a mixture having the desired fuel con-

tent and the velocity of flow through the primary mixture conduits when the air throttle is not open, is sufficient to convey this primary mixture to the intake ports almost immediately following any movement of the throttle. There is, therefore, no need for a temporary supply of additional fuel and if such fuel is supplied, there is a tendency for the mixture to become temporarily overrich following opening movements of the throttle during low speed operation. The device disclosed herein eliminates this difficulty by supplying additional fuel only on opening movements of the air throttle, such additional fuel being necessary to compensate for the tendency to temporarily lean the mixture, which occurs when the air throttle is opened to admit secondary air.

While the form of embodiment of the present invention as herein disclosed, constitutes a preferred form, it is to be understood that other forms might be adopted, all coming within the scope of the claims which follow.

What is claimed is as follows:

1. A charge forming device for internal combustion engines comprising a mixture passage, means supplying fuel and air thereto, a mixture throttle, a secondary air passage supplying air to said mixture passage, a manually operable air throttle controlling the flow of air through said secondary passage, and means operated by said air throttle for enriching the mixture on opening movements thereof.

2. A charge forming device for internal combustion engines comprising a mixture passage, means supplying fuel and air thereto, a mixture throttle, a secondary air passage supplying air to said mixture passage, a manually operable air throttle controlling the flow of air through said secondary passage, a fuel pump for supplying additional fuel to said mixture passage and a common operating means for said air throttle and the fuel pump.

3. A charge forming device for internal combustion engines comprising a secondary mixing chamber, a primary mixture passage adapted to deliver a primary mixture of fuel and air thereto, means for supplying fuel and air to said primary mixture passage a mixture throttle controlling the flow of primary mixture, a secondary air passage supplying air to said secondary mixing chamber, a manually operable air throttle for regulating the flow through said air passage, and means for enriching the mixture only on opening movements of the air throttle.

4. A charge forming device for internal combustion engines comprising a secondary mixing chamber, a primary mixture passage adapted to deliver a primary mixture of fuel and air thereto, means for supplying fuel and air to said primary mixture passage a

- 5 mixture throttle controlling the flow of primary mixture, a secondary air passage supplying air to said secondary mixing chamber, a manually operable air throttle for regulating the flow through said air passage, and a pump for supplying additional fuel to the mixture only on opening movements of the air throttle.
- 10 5. A charge forming device for internal combustion engines comprising a secondary mixing chamber, a primary mixture passage adapted to deliver a primary mixture of fuel and air thereto, means for supplying fuel and air to said primary mixture passage a mixture 70
15 throttle controlling the flow of primary mixture, a secondary air passage supplying air to said secondary mixing chamber, a manually operable air throttle for regulating the flow through said air passage, and a pump 75
20 for supplying additional fuel to the secondary mixing chambers only during operation of the air throttle.
- 25 6. A charge forming device for internal combustion engines comprising a secondary mixing chamber, a primary mixture passage adapted to deliver a primary mixture of fuel and air thereto, means for supplying fuel and air to said primary mixture passage a mixture 80
30 throttle controlling the flow of primary mixture, a secondary air passage supplying air to said secondary mixing chamber, a manually operable air throttle for regulating the flow through said air passage, a pump for 85
35 supplying additional fuel to the secondary mixing chambers and an operating connection for said pump extending to the air 90
throttle.
- 40 7. A charge forming device for internal combustion engines comprising a secondary mixing chamber, a primary mixture passage adapted to deliver a primary mixture of fuel and air thereto, means for supplying fuel and air to said primary mixture passage, a secondary throttle controlling admission of 95
45 air to said secondary mixing chamber, a primary throttle controlling the flow through said primary mixture passage, a fuel pump for supplying additional fuel to enrich the mixture, means for operating the secondary 100
50 throttle during only a part of the opening movement of the primary throttle, and means for operating the pump only during opening movement of the secondary throttle.
- 55 8. A charge forming device for internal combustion engines comprising a mixture passage adapted to supply a combustible mixture to the intake port of the engine, means for supplying fuel and air to said passage, a throttle therein, a secondary air passage adapted to supply additional air to said 105
60 passage at a point adjacent said intake port, an air throttle for regulating the flow through said passage, and means for supplying additional fuel at the point where secondary air 110
65 is mixed with the primary mixture, said means being operated only during the opening movement of said air throttle.
- 70 9. A charge forming device for internal combustion engines comprising a mixture passage adapted to supply a combustible mixture to the intake port of the engine, means for supplying fuel and air to said passage, a throttle therein, a secondary air passage adapted to supply additional air to said passage at a point adjacent said intake port, an air throttle for regulating the flow through said passage, and a pump connected with the air throttle for operation thereby, and adapted to supply additional fuel at the point where secondary air is mixed with the primary mixture.
- 75 10. A charge forming device for internal combustion engines comprising a plurality of secondary mixing chambers, a plurality of primary mixture passages adapted to deliver a primary mixture of fuel and air to said secondary mixing chambers, a secondary air passage adapted to supply additional air to all of said secondary mixing chambers, an air throttle therein controlling the flow of air therethrough and means operated only on opening movements of the secondary throttle for supplying additional fuel to the secondary mixing chambers simultaneously.
- 80 11. A charge forming device for internal combustion engines comprising a plurality of secondary mixing chambers, a plurality of primary mixture passages adapted to deliver a primary mixture of fuel and air to said secondary mixing chambers, a secondary air passage adapted to supply additional air to all of said secondary mixing chambers, an air throttle therein controlling the flow of air therethrough, a fuel pump, a branched delivery conduit extending from said pump to all of said secondary mixing chambers to supply additional fuel thereto simultaneously and means for operating said pump only on opening movements of the air throttle.
- 85 12. A charge forming device for internal combustion engines comprising a mixture passage, means supplying fuel and air thereto, a mixture throttle, a secondary air passage supplying air to said mixture throttle, a manually operated air throttle controlling the flow of air through said air passage a fuel pump operated by said air throttle for supplying additional fuel to the mixture passage during the acceleration period, and means for rendering the pump effective when the air 110
90 throttle is opened rapidly, but rendering the pump ineffective when the throttle is opened slowly, said means comprising a valve operated by the pump piston on relatively rapid movements thereof.
- 95 13. A charge forming device for internal combustion engines comprising, a primary mixture passage, means for supplying fuel and air thereto, a secondary mixing chamber into which said mixture passage delivers, a 115
100
- 105
- 110
- 115
- 120
- 125

mixture throttle controlling the mixture flow, a secondary air passage supplying air to said secondary mixing chamber, a manually operable air throttle controlling the flow of air 5 through said air passage, a fuel pump operated by said air throttle for supplying additional fuel to the secondary mixing chamber, a delivery conduit for conveying fuel from said pump to the secondary mixing chamber 10 and means for maintaining said delivery conduit full of fuel at all times.

14. A charge forming device for internal combustion engines comprising, a primary mixture passage, means for supplying fuel 15 and air thereto, a secondary mixing chamber into which said mixture passage delivers, a mixture throttle controlling the mixture flow, a secondary air passage supplying air to said secondary mixing chamber, a manually operable air throttle controlling the flow of air 20 through said air passage, a fuel pump operated by said air throttle for supplying additional fuel to the secondary mixing chamber, a delivery conduit for conveying fuel from said pump to the secondary mixing chamber 25 and a single means for controlling the flow of fuel from the pump and for maintaining the delivery conduit full of fuel at all times.

15. A charge forming device for internal 30 combustion engines comprising a main air manifold communicating with the engine intake ports, a plurality of secondary mixing chambers formed therein adjacent said ports, an air inlet supplying air to the manifold, a plurality of primary mixture passages adapted 35 to deliver a primary mixture of fuel and air to the secondary mixing chambers, a mixture throttle, a secondary air passage for conveying air from said inlet to the secondary 40 mixing chambers and means operated by the air throttle on opening movements thereof, for supplying additional fuel to all of the secondary mixing chambers simultaneously, to enrich the mixture during the acceleration 45 period.

16. A charge forming device for internal combustion engines comprising a secondary mixing chamber located adjacent to the engine intake port, a primary mixing chamber 50 relatively remote from the secondary mixing chamber, a primary mixture passage connecting said chambers, means for supplying fuel and air to said mixture passage, a mixture throttle controlling the flow of primary 55 mixture, a secondary air passage supplying additional air to the secondary mixing chamber, a manually operable air throttle for controlling the admission of said additional air and means operated by the air throttle for 60 supplying additional fuel directly to the secondary mixing chamber on opening movements of said throttle to enrich the mixture for acceleration.

17. A charge forming device for internal 65 combustion engines comprising, a mixture

passage, means for supplying fuel and air thereto and a pump for supplying additional fuel thereto during the acceleration period, a secondary air passage supplying additional air to the mixture passage, a manually operable air throttle for controlling the flow of said additional air, said pump comprising a piston connected to the air throttle, a cylinder in which said piston is received and having a fuel delivery outlet, a spring closed valve normally closing said outlet, and means operated by the pump piston for opening said valve on the pumping stroke of said piston. 70 75

18. A charge forming device for internal combustion engines comprising, a mixture 80 passage, means for supplying fuel and air thereto and a pump for supplying additional fuel thereto during the acceleration period, a secondary air passage supplying additional air to the mixture passage, an air throttle for 85 controlling the flow of said additional air, said pump comprising a piston connected to the air throttle, a cylinder in which said piston is received and having a fuel delivery outlet, a valve for closing the delivery outlet, 90 means operated by the pump piston for opening said valve and means for closing the valve when the piston is at rest.

19. A charge forming device for internal combustion engines comprising, a mixture 95 passage, means for supplying fuel and air thereto and a pump for supplying additional fuel thereto during the acceleration period, a secondary air passage supplying additional air to the mixture passage, an air throttle for 100 controlling the flow of said additional air, said pump comprising a piston connected to the air throttle, a cylinder in which said piston is received and having a fuel delivery outlet, a valve for closing the delivery outlet, 105 means operable by the pressure of the pump piston on rapid opening movements thereof for opening said valve, and means for holding the valve closed with sufficient force to prevent the opening of the valve on 110 slow movements of the valve when the pressure exerted by the piston on the valve opening means is low.

20. A charge forming device for internal combustion engines comprising, a mixture 115 passage, means for supplying fuel and air thereto and a pump for supplying additional fuel thereto during the acceleration period, a secondary air passage supplying additional air to the mixture passage, an air throttle for 120 controlling the flow of said additional air, said pump comprising a piston having a recess therein and connected to the air throttle for movement therewith, a cylinder in which the piston is slidable and provided with a fuel delivery outlet, a valve for closing said outlet, an auxiliary piston slidable in said recess and connected to the valve whereby the 125 valve is operated by said auxiliary piston.

21. A charge forming device for internal 130

combustion engines comprising, a mixture passage, means for supplying fuel and air thereto and a pump for supplying additional fuel thereto during the acceleration period, a
5 secondary air passage supplying additional air to the mixture passage, an air throttle for controlling the flow of said additional air, said pump comprising a piston having a recess therein and connected to the air throttle
10 for movement therewith, a cylinder in which the piston is slidable and provided with a fuel delivery outlet, a valve for closing said outlet, an auxiliary piston slidable in said recess and connected to the valve sufficient
15 clearance being provided between the auxiliary piston and the wall of the recess to permit slow movements of the pump piston without accompanying movement of the valve operating piston under certain operating conditions.
